(57) **CLAIM**

I claim the ornamental design for a wrist support, as shown and described.

DESCRIPTION

FIG. 1 is a perspective view of my new design for a right-handed wrist support, assembled and installed on a right hand, with the broken lines showing environmental association matter for illustrative purposes only and forming no part of the claimed design;

FIG. 2 is a front view thereof;

FIG. 3 is a rear view thereof;

FIG. 4 is a view thereof from one side;

FIG. 5 is a view thereof from the other side;

FIG. 6 is a top view thereof;

FIG. 7 is a bottom view thereof;

FIG. 8 is a plan view thereof, unassembled from the front; and,

FIG. 9 is a plan view thereof, unassembled from the rear. My new design for a left-handed wrist support for the left hand is a mirror image of the designs represented in FIGS. 1-9.
